US00D626091S

(12) **United States Design Patent**
Neitzel et al.

(10) **Patent No.:** **US D626,091 S**
(45) **Date of Patent:** **** Oct. 26, 2010**

(54) **CONNECTOR HOUSING**

(75) Inventors: **Edward Neitzel**, Elkton, MD (US);
Robert Bernstine, Chesapeake City, MD
(US)

(73) Assignee: **Gore Enterprise Holdings, Inc.**,
Newark, DE (US)

(**) Term: **14 Years**

(21) Appl. No.: **29/357,014**

(22) Filed: **Mar. 5, 2010**

Related U.S. Application Data

(63) Continuation-in-part of application No. 29/318,985,
filed on Jun. 2, 2008, now Pat. No. Des. 614,584.

(51) **LOC (9) Cl.** **13-03**

(52) **U.S. Cl.** **D13/156**; D23/259

CLAIM

The ornamental design for a connector housing, as shown.

DESCRIPTION

FIG. 1 is a perspective view of a connector housing showing our new design;

FIG. 2 is a top view thereof;

FIG. 3 is a bottom view thereof;

FIG. 4 is a side view thereof;

FIG. 5 is another side view thereof; and,

FIG. 6 is another perspective view thereof.

1 Claim, 2 Drawing Sheets
